UNITED STATES PATENT OFFICE

SIDNEY B. GORBUTT, OF PORTLAND, OREGON

FRAME FOR FLAT SCREENS

Application filed May 31, 1930. Serial No. 458,352.

This invention relates generally to the paper making industry, and particularly to flat screens such as are commonly used in this industry.

5 The main object of this invention is the construction of a new form of frame for flat screens which will overcome many of the difficulties ordinarily encountered in the use of frames consisting of a plurality of parts which are bolted together.

10 The second object is to construct a one piece frame for flat screens which will be light of weight as compared with the usual type of cast frame and which will be sufficiently rigid to enable same to be assembled in the shop and transported on cars without danger of distortion.

15 The third object is to construct a frame for flat screens in which the desired inclination of the screens can be obtained without the employment of a large number of patterns, as is necessary where cast structures are employed.

20 The fourth object is to construct a frame having the desired rigidity without requiring the performance of an objectionable amount of machine work in order to secure a proper fit between contacting parts.

25 The fifth object is to construct a frame from structural steel the parts of which are made integral with each other by a welding process for the purpose of eliminating the difficulties usually experienced from warped or distorted frames, which is commonly the case when same are made from castings.

30 The sixth object is to construct a frame which will adapt itself to any inequalities in the foundation without danger of fracture.

35 The seventh object is to make a frame for flat screens which, as compared with the present type of cast frame, weighs less, costs less, is stronger in tension, has greater stiffness, requires a smaller factor of safety on account of its more uniform strength, eliminates pattern expense, reduces the cost of and the amount of machining required and also wasted labor and material caused by the discovery of a defective part in a casting after considerable work has been done thereon.

40 The eighth object is to so construct the

frame that the liquor or pulp need not come in contact with any metal, either within the screen or within the outlet.

These, and other objects, will become more apparent from the specification following as illustrated in the accompanying drawings, in which:

45 Fig. 1 is a perspective view of the completed frame.

Fig. 2 is a plan of one end of the frame.

50 Fig. 3 is a perspective view of the upper corner forming parts before assembly.

Fig. 4 is a view of the parts shown in Fig. 3 after being assembled.

55 Fig. 5 is a front elevation of the screen frame.

Fig. 6 is an end elevation of the screen frame.

60 Fig. 7 is an enlarged section along the line 7—7 in Fig. 6.

Fig. 8 is a section taken along the line 8—8 in Fig. 7.

65 Fig. 9 is a section taken along the line 9—9 in Fig. 5.

70 Similar numbers of reference refer to similar parts throughout the several views.

75 Referring in detail to the drawings, there is shown a frame consisting of the upright legs 10 and 11 whose lower ends are joined in pairs by means of the cross ties 12 upon which rests the I beam 13 which forms a support for the bearings 14 of the shaft 15, one end of which carries a pulley 16 and is supported by a standard 17.

80 Around the top of the legs 10 and 11 are mounted the angle bars 18 and 19 whose ends 20 and 21 are cut as shown in Fig. 3, in order that the vertical faces 22 thereof may engage the outer sides of the legs 10. Secured against the inner faces 22 of the angle bars 18 are a plurality of angle clips 23. The clips 23 are employed for the purpose of supporting the spring board mechanism placed directly under the diaphragms, the details of which are well understood.

85 Between the bars 18 are secured the angle bars 24. Gusset plates 25 and 26 stiffen the fastenings between the bars 18 and their respective legs 10 and 11. Diagonally between the legs 11 are placed the braces 27 which are 90

95

100

preferably in the form of angle bars. Similar braces 28 are placed between each pair of legs 10. Every fastening between the parts thus far described is welded, in order that the finished frame shall be, for all practical purposes, a one piece structure.

Underneath the legs 10 and 11 are welded the flat feet 29 by means of which the frame may be secured to a foundation, if desired.

10 Mounted on top of the bars 18 and 19 and upon the cross bars 24 are the wooden bunk members 30 and 31 to which are secured, by means of the brass bolts 32, the rubber diaphragms 33. The upper portion 34 of the 15 bunk members 30 and the portions 36 of the bunk members 31 are held in their respective supports by means of the bolts 35. It is desirable to make the portions 30 and 31 of the bunk members of separate pieces of material 20 from the upper portions 34 and 36, to which they may be secured in any convenient manner. Resting on the portions 34 and 36 of the bunk members is the vat itself which consists of a box-like structure 37 across which are 25 mounted the supports 38 for the screen securing bars 39, by means of which the edges of the perforated metal screen plates 40 are firmly secured in a manner which is well understood in the art.

30 The vat 37 is secured upon the bunk portions 34 by means of the clamping bolts 41, the upper end of which is provided with a link 42 which engages a hook 43 secured on the outside of the vat 37. The lower end of 35 each bolt 41 is threaded and extends through an angle clip 44 secured to a member 18. On the outer side of one member 18 is placed a wooden spacer 45 against which is secured the side 46 of the flow box. Outlet openings 40 47 extend through the side 46 the spacer 45 and the bunk portion 34.

Numerous details of construction have been omitted for the purpose of simplifying the description of this invention. For example, it 45 is well understood that a vibratory movement is imparted to the diaphragm 33 by means of a shaker mechanism operated by the shaft 15, preferably by means of a connecting rod 48. The precise manner in which this is accomplished is immaterial as far as this invention 50 is concerned.

While at first glance it may appear that there has merely been constructed a frame of structural members to take the place of 55 similar frames which have previously been made of heavy castings, it will be borne in mind that these devices are assembled at the factory and are shipped to their destination and that any undue distortion of the parts, 60 if made of cast iron, might be disastrous in view of the relatively great length thereof. As previously stated, owing to the uncertain nature of the cast iron structure a high factor of safety must be employed. This, of 65 course, greatly increases the cost and weight

and makes it impossible, under present methods, to unite the various frame sections into a unitary or one piece structure.

Referring particularly to the connection between the vat 37 and the frame itself it 70 will be seen that by interposing the bunk members 30 and 31 that the liquor does not come into contact with any of the metal of the frame, either within the vat 37 or when passing through the outlets 47 into the flow 75 box. This is highly desirable, owing to the manner in which the stock attacks ordinary metals such as steel and cast iron and which naturally results in a discoloration of the stock coming in contact therewith.

It is a well known fact that frames for flat screens have for many years been constructed of cast iron which, owing to their nature, had to be strongly built; I therefore do not intend to cover such devices broadly, but I do intend to cover all such forms and modifications as fall fairly within the appended claim.

I claim:

A unitary structural steel frame for supporting flat screens consisting of a rectangular top formed of angle bars having their outer edges downturned and the top of their end members flush with the top of their side members, a plurality of pairs of transversely spaced legs supporting said angle bars, each pair of legs having a cross tie between the lower ends thereof, and a central longitudinal tie on the top side of said cross tie and normal thereto forming a support for the operating mechanism of the screen diaphragm.
